UNITED STATES PATENT OFFICE.

IRVING J. GILL, OF SAN DIEGO, CALIFORNIA.

MEANS FOR REINFORCING WALLS.

1,202,990.

Specification of Letters Patent. Patented Oct. 31, 1916.

Application filed October 2, 1913. Serial No. 793,066.

To all whom it may concern:

Be it known that I, IRVING J. GILL, a citizen of the United States, residing at San Diego, in the county of San Diego and State 5 of California, have invented a new and useful Means for Reinforcing Walls, of which the following is a specification.

In building structures heretofore made the margins of the window and door openings have not been sufficiently reinforced, so that the weight of the portion of the wall above the lintel tends to deflect the center of the lintel, and the weight of the portions of the wall transmitted through the jambs 15 tends to raise the center of the sill.

An object of this invention is to overcome the foregoing difficulties by my special construction for reinforcing the walls of building structures.

20 The structure may be made by bending a reinforcing member into a frame having the shape and proportion of the desired opening, placing such bent-up frame either in its final position in the structure or placing said frame horizontally on a table, and then pouring concrete around the reinforcing frame so as to, more or less, embed said frame in the concrete and cause the frame to become an integral part of the wall.

30 In the completed structure the frame becomes a form for the opening during the construction of the wall and likewise becomes a permanent reinforcing member for the margins of the opening.

35 I may in some instances employ but one form of reinforcing member bent to form a reinforcing frame, and in other instances I may employ such reinforcing frame together with other forms of reinforcing 40 members, such as rolled rods of any desired shape ordinarily employed as reinforcing members in reinforced concrete construction. These reinforcing rods may be plain, twisted or of any preferred or desired construction, 45 and when said rods are used they may be suitably anchored to the reinforcing frame.

Another object is the production of suitable bent and rolled forms of reinforcing members, adapted to secure the best results.

50 Besides the forms of frames invented and employed by me in this instance, it is understood that I may employ the forms of metal

window frames shown and described in my previous invention for building construction, filed July 11, 1912, Serial No. 708,911, or 55 that I may employ any other suitable forms which I may invent in the future.

I am aware that concrete has been poured around wooden frames and also that metal has been used as a sheathing for wooden 60 frames in fireproof building construction but I am not aware that a reinforcing member has been formed into a frame, and that said frame has then been incorporated into a wall as an integral part thereof in the process of making the wall so that the frame truly forms a tension member for the lintel, jambs 65 and sill of an opening in the wall.

Other objects and advantages may appear in the drawings filed herewith and in the 70 subjoined detail description.

The accompanying drawings illustrate the invention.

Figure 1 is an external elevation of a wall built in accordance with and embodying this invention. Fig. 2 is an enlarged fragmental detail of some of the reinforcing members shown in Fig. 1. Fig. 3 is a reduced plan section on line indicated by z^1 , Fig. 2. Fig. 4 is an enlarged fragmentary 80 view of some of the parts shown in Fig. 1 with the window sashes in place. Fig. 5 is an enlarged plan section on irregular line indicated by z^2-z^3 , Fig. 4. Fig. 6 is a perspective view of a fragment of one of the 85 reinforcing frames in the preceding views. Fig. 7 is a fragmentary plan section analogous to Fig. 5, but including a different form of reinforcing frame.

The wall 1 may be of any suitable material as brick, stone, concrete or the like and, if of concrete, may be poured in place by the use of forms, not shown but well-known in the art, or may be poured in a horizontal position and subsequently moved 95 into vertical position as shown, for instance, in the patent to Aiken for method and apparatus for constructing concrete buildings, No. 1,023,349, patented April 16, 1912.

The wall 1 is provided with reinforcing 100 members of any suitable design, one of the reinforcing members being bent to form a door frame 2 for an opening as the doorway 3, and another of the reinforcing members

being bent to form a window frame 4 for a window opening 5. The wall 1 may be further reinforced by reinforcing members in the form of rods 6, or the like, of any desired shape and arranged at intervals in the manner well-known in the art, though it may not be necessary to employ the rods 6 in small structures.

The reinforcing frames 2, 4 entirely surround the openings 3, 5 respectively and comprise tension lintel members 7, tension jamb members 8, and tension sill members 9.

The reinforcing frames 2, 4 may be bent from sheet or strip metal in the form shown in Figs. 1 to 6 inclusive, or in the forms shown in my hereinbefore mentioned invention, or may be bent in any other desired forms; or said frames may be formed from rolled members as in Fig. 7.

20 In some instances, as in said former invention and as in Fig. 7, the reinforcing frames 2, 4 may each be formed of but one piece of material, and, in other instances, where the shape of the piece will not admit 25 of its being bent at the corners of the opening, the lintel, jamb and sill members 7, 8, 9 may be provided with mitered ends 10 as in Fig. 2 soldered or otherwise securely joined to one another.

30 The reinforcing frames 2, 4 may be provided at intervals with perforations 11 as in Figs. 1 to 6 through which some of the constituents of the wall will pass so as to firmly anchor the frame in place, and the frame 35 may be additionally anchored, if desired, by connecting the reinforcing rods 6 thereto in any suitable manner as for instance by providing the rods with hook ends 12 to hook over the edges of the perforations 11.

40 In the form shown in Fig. 6 the reinforcing frame is bent to form a frame face 13 and anchor leg 14 at right angles to one another and is bent to form a slanting anchoring leg 15 connecting the outer ends 45 of the frame face and leg 13, 14; altogether substantially forming a triangular member of great strength. The edges of the legs 14, 15 are joined in any suitable manner and, in this instance, the leg 14 is bent at 50 its edge to form a channel 16 to receive the edge of the leg 15, and the joint may be further strengthened, if desired, by rivets or the like, not shown.

In the form shown in Fig. 7 the reinforcing frame is provided with the frame face 13, as in the form shown in Fig. 6, and is provided at right angles thereto with an anchor arm 17 terminating in a flanged head 18, said leg being perforated to receive the 55 hook ends 12 of the reinforcing rods 6. Each frame face 13 is offset to form a stop 19 which is provided with a narrow tongue 20 adapted to contact with the face of the sash 21, said tongue being spaced 60 apart from the edges of the sash to form

a channel or groove 22 so that, when water works in between the edges of the sash 21 and frame face 13, capillary attraction will be broken up at the channel in order that said water will not pass the 70 stop and will be excluded from the inside of the window. The channel 22 also prevents to a maximum degree the entrance of wind as it forms a chamber or reservoir in which the air circulates.

75 The reinforcing frame bent from sheet metal as in Figs. 5 and 6 may be provided with a reinforcing strip 23 fastened by rivets 24 or the like along the inner side of the frame face 13 so that the fastenings 25 80 of the hinges 26 can be passed through the frame face and through said reinforcing strip.

In practice reinforcing frames 2, 4 will be placed in those positions where door and 85 window openings are desired and, if further reinforcement is desired, reinforcing rods 6 will be placed at intervals and anchored to the reinforcing frames. This 90 may all be accomplished in a vertical position in the manner generally employed in connection with pouring of the walls of large building structures, or may be done in a horizontal position in accordance with 95 the method outlined in the hereinbefore mentioned patent to Aiken. When the reinforcing members have all been thus placed in position, the concrete is then poured around the frames to more or less embed them in the concrete and cause them to become 100 integral parts of the wall.

I am aware that finishing strips of various kinds have been anchored in concrete and I do not broadly claim such construction but it is noted that I form reinforcing 105 wall members into door and window frames and that I then incorporate said door and window frames into the walls of the building structure as integral parts thereof in the process of making the wall, so that the 110 lintels, jambs and sills not only have compression members formed by the concrete at the margins of the openings but also have tension members co-operating therewith and formed by the frames.

115 I claim:

A metal door and window frame comprising a reinforcing frame provided at intervals with perforations through which some 120 of the constituents of the wall may pass so as to firmly anchor the frame in place and also affording seats for reinforcing rods, which may be hooked over the edges of the perforations; said reinforcing frames being 125 bent to form a frame face and an anchor leg at right angles to one another and to form a slanting anchor leg connecting the outer ends of the frame face and leg all together, the edges of the legs being joined together, the frame face being offset to 130

form a stop which is provided with a narrow tongue adapted to contact with the face of a sash, said tongue being spaced apart from the edges of the sash to form a channel or groove substantially as and for the purpose set forth.

In testimony whereof, I have hereunto

set my hand at Los Angeles, California, U.S.A.
25th day of September, 1918.

IRVING J. GILL.

In presence of—

JAMES R. TOWNSEND,
GEORGE H. HILES.
